ELECTRIC COMMUNICATION SYSTEM

Harry R. Allensworth, Columbus, Ohio

Application March 8, 1937, Serial No. 129,619

4 Claims. (Cl. 179—5)

My invention relates to electric communication systems and more particularly to that field or subject matter known to the art as emergency communication and has for its object new and improved means whereby the scope of usefulness of certain kinds of communication systems is enlarged, expanded and extended beyond otherwise inherent limitations and restrictions.

According to my invention these objects are attained by new and novel means comprising electric circuits and networks whereby telephonic signaling and communication upon any suitable signal circuit is accomplished without in any way hindering the operation of, or impairing the normal functioning of, the signal circuit.

My invention will be best understood from a consideration of the following detailed description taken in connection with the accompanying drawing forming a part of this application; with the understanding, however, that the invention is not confined to the one practical application herein selected for purposes of illustration nor is the invention confined to any strict conformity with the showing of the drawing which may be changed or modified so long as such changes and/or modifications mark no material departure from the salient features of the invention within the scope of the appended claims.

Illustrative of one, only, of the important practical applications of my invention as shown in the single figure of the drawing: The conventional firm alarm signal (box) circuit is a closed, metallic, constant current circuit comprising battery, signal recording and signal sounding devices and a multiplicity of signal boxes, in series. The circuit is ordinarily employed exclusively for the communication of fire alarm signals. Attempts have been made to expand and enlarge the usefulness of fire alarm signal circuits by employing the circuit for telephonic communication. Where this is done, a telephone transmitter and receiver are usually connected in the circuit in series at one of the signal boxes. Similarly, at the central office a telephone transmitter and receiver are connected in the circuit and telephonic communication from the box to the central office and vice versa, is made possible. In closed circuit systems the attention of the central office attendant is attracted to a telephone call from a signal box by opening and closing the circuit—by means provided at the signal box—a prearranged number of times thus “striking” a signal in the central office. Telephonic communication under such circumstances is not

of the best. Furthermore, there is ever present the possibility of mutilating an alarm signal.

By the application of my invention to this circumstance telephonic communication of very high quality is made possible and the possibility of, in any way, impairing the normal functioning of the signal circuit is eliminated.

Referring now to the accompanying drawing: L₁ and L₂ are the two sides of a fire alarm signal (box) circuit comprising battery 1, recording device 2, sounding device 3 and signal boxes 4, 5, 6 and 7, in series; any acceptable number of signal boxes may be comprised in the circuit, as indicated by dotted lines from boxes 4 and 7, including boxes 5 and 6. The circuit is normally closed. Each box, in addition to other functional devices, is equipped with a jack or other suitable means of connecting a telephone or other device in series with the circuit. Such a device (8) in the form of a conventional jack, 10 normally closed, is shown as part of signal box 7. Operatively associated with the above well known emergency communication system, in the manner hereinafter disclosed, is an electric communication network comprising plug 9; the two conductors connected to 9; P₁, P₂, P₃, S and C; hand set HS comprising telephone transmitter T and telephone receiver R; break-make push button 10 and impulse emitter 11; together and collectively constituting a portable telephone. Also, 20 operatively associated with said emergency communication system is an electric communication system comprising line relays LR and LR₂, line signal LL, cut-off relay CO, answering jack 12 and multiple jack 13, with associated circuits 25 and appurtenances, together and collectively constituting a telephone switchboard line circuit operatively associated with L₁ and L₂ by means of condensers 14 and 15.

P₁, P₂ and P₃ are three primary windings of a 40 four winding transformer; S, the fourth winding, is secondary to P₁, P₂ and P₃. The three said primary windings together with telephone transmitter T are so connected as to form a divided circuit bridged by condenser C at points 45 15' and 16.

The armature of impulse emitter 11 is a reed of magnetic material or an armature suitably poised on a leaf spring or other suitable means whereby the armature operates at the proper 50 vibration frequency.

Assume now that plug 9 be inserted in jack 8; thereby the network comprising P₁, P₂, P₃, S, C, HS, 10 and 11 is connected in the signal circuit (L₁, L₂) and becomes operatively associated 55

- therewith. Break-make push button 10, upon being operated, disconnects telephone transmitter T from the network and substitutes therefore impulse emitter 11 which upon becoming energized 5 attracts its armature which closes 17 thus short circuiting 11 which is thereby deenergized and its armature releases, opening 17; whereupon the same cycle of operation is repeated and continued so long as 18 is held closed.
- 10 The operation of 11 thus sets up an undulatory impulse sequence or train in the transformer primary which undulatory impulse sequence is impressed and superinduced in the signal circuit by the operation of the telephone network. Impulse emitter 11 may take the form of the well known electric buzzer, the operation of which will produce similar results in the transformer primary and network.
- 15 Furthermore, when break-make push button 10 is operated, 19 is closed shunting R and S. Shunting S reduces the impedance of the transformer primaries to impulse sequences emitted by the operation of 11. Additionally, both booster and antisidetone characteristics are incorporated in said telephone network, as is shown.
- 20 The impedances of 2 and 3 causes them to function as retardations or reactors to the undulatory current impulse sequences superinduced in L1, L2 by the operation of 11; also, to current undulations superinduced in L1, L2 by the operation of transmitter T in response to sound waves.
- 25 The undulatory impulse sequences impressed and superinduced in L1, L2 by the operation of 11 cause condensers 14 and 15 to charge and discharge with the rise and fall of the E. M. F. of said impulses. This said charge and discharge of condensers 14 and 15 superinduces corresponding alternating current impulse sequences in LR and 20 which causes LR to operate.
- 30 The operation of LR closes 21 which puts battery through the winding of slow to operate relay LR2, as is shown. LR2 being slow to operate will respond only to a prolonged, momentarily, closing of 21. Accordingly, slow to operate relay LR2 will not respond to comparatively infrequent charging and discharging of condensers 14 and 15 due to rise and fall of E. M. F. in L1 and L2 caused by the operation of the signal circuit, or other incidental charge and discharge of 14 and 15.
- 35 The operation of LR2 closes 22 and 23. The closing of 22 causes line signal LL to operate. The closing of 23 shunts the telephone switchboard line circuit at points 24 and 25 and holds LR operated which holds LR2 and LL operated until a switchboard plug is inserted in jack 12 or 13, which action puts battery on the sleeve of the 40 jack thus operating cut-off relay CO which releases LR which in turn releases LR2. Thus the line signal is restored by the opening of 22; the holding shunt is opened by the opening of 23 and the right back contact of CO.
- 45 The opening of the holding shunt 24, 25 by the opening of right back contact of CO eliminates the possibility of an annoying click in the telephone switchboard operator's receiver in case the tip and ring of plug inserted in 12 or 13 engage 40 their respective contacts prior to the release of LR2 and the opening of 23.
- 50 The operation of transmitter T in response to sound waves causes current undulations to be set up in the transformer primary which current undulations are impressed and superinduced in the 55 signal circuit by the operation of the aforesaid network. The rise and fall of the E. M. F. of said current undulations causes condensers 14 and 15 to charge and discharge which superinduces corresponding alternating current impulses in the said telephone line circuit and telephonic communication from any one of the signal boxes 4, 5, 6, 7 in L1, L2 and any telephone connected with the said telephone line circuit, by means of jacks 12, 13, is effectuated. Similarly will the 60 operation of a transmitter (not shown) associated with said telephone line circuit by means of jacks 12, 13 cause condensers 14 and 15 to charge and discharge thus superinducing corresponding alternating current impulses in said signal circuit and telephonic communication from a telephone or telephones connected to said telephone line circuit and a telephone or telephones connected in and to L1, L2 at any of the said signal boxes 4, 5, 6, 7 is effectuated.
- 55 Thus, in this illustrative practical application of my invention, are the closed, constant current signal circuit and the normally open telephone line circuit operatively associated as an electric communication system whereby the scope of usefulness of the signal circuit is enlarged, expanded and extended by making it readily available for telephonic communication without, in any way, impairing its normal functioning.
- 60 What is claimed is:
1. A telephone line circuit comprising a line relay responsive to alternating current impulse sequences, a signal circuit operatively associated therewith, and a condenser in series between each side of said telephone line circuit and each side of said signal circuit said condensers impressing in said telephone circuit said impulses; operation of said condensers being a function of variations of E. M. F. in said signal circuit; a telephone network operatively associated with the aforesaid signal circuit and comprising a short circuiting electromagnetic relay; the aforesaid variations of E. M. F. being superinduced in said signal circuit by the operation of said relay and said network. 65
2. An electric communication system comprising a telephone circuit, a signal circuit, two condensers, each of the two condensers being in series between each of the two sides of the two circuits, and a telephone network comprising a telephone transmitter and a transformer, said network being operatively associated with said signal circuit and superinducing therein current undulations corresponding to the variation of E. M. F. in said network, the aforesaid condensers superinducing in the aforesaid telephone circuit corresponding alternating current impulses. 70
3. An electric communication system comprising a metallic signal circuit, a telephone network comprising means of superinducing undulatory signal impulses on said signal circuit, a telephone circuit, and condensers in all connections between said signal system and said telephone circuit, the variation of E. M. F. of said undulatory impulses causing said condensers to superinduce corresponding alternating current impulses in said telephone circuit; said telephone circuit comprising battery, a primary line relay responsive to said alternating current impulses, a secondary slow to operate line relay responsive to prolonged operation of said primary line relay, a line signal responsive to operation of said secondary line relay, a normally open shunt circuit across said telephone circuit said shunt circuit being closed by the operation of said secondary line relay; and a cut-off relay the operation of said cut-off relay. 75

disconnecting said battery and said primary line relay from said telephone circuit and opening said shunt circuit.

4. An electric communication network comprising a telephone receiver, a transformer and a switch said switch comprising a plurality of contacts, the operation of said switch closing two

of said contacts, the closing of one of said contacts inserting signal impulse emitting means in the network and the closing of the other of said contacts short circuiting the secondary winding of said transformer and short circuiting said telephone receiver. 5
